Jesse Hutchinson

UNITED STATES PATENT OFFICE.

CHARLES V. MAMMEN, OF YOUNGSTOWN, OHIO.

TIMBER TONGS.

Application filed October 20, 1925. Serial No. 63,747.

My invention relates to tongs, designed for the handling of logs, railroad ties and other timbers, the object and purpose being to provide a strong, efficient and cheaply 5 constructed tool for this purpose.

In the accompanying drawings, Figure 1 represents a top plan view of my tool applied to a stick of timber; Figure 2 represents a side view, also applied to a stick of 10 timber; Figure 3 is a view partially in section on line 3—3, Figure 2; Figure 4 is a detail view of the tong or gripping jaws proper; Figures 5, 6 and 7 are fragmentary views, showing different methods by which 15 the handles may be attached to each other.

1—1 represent the handles, each carrying at its inner end what may be termed the union bracket 2, and these two brackets are 20 swingingly joined by means of the pin or rivet 3, thus permitting the free or outer ends of the handles to move freely away from and towards each other. Rigidly secured to the under face of one of the handles, at its inner end, is the brace or shoe 4, 25 designed to rest against the timber being handled. Loosely attached to the under face of each handle, intermediate its ends, as at 5, is the bar 6, carrying at its outer or free end a hook or curved jaw member 7. 30 The two bars 6—6 are pivoted together adjacent their centers by the pivot 8, thus forming movable opposing gripping jaws.

With this construction it is obvious that as the outer ends of the handles 1—1 are separated by the operator, the hooks or jaw members 7—7 will open, thus permitting the two jaws to grasp the opposite sides of the object to be handled, and as upward or lifting pressure or force is brought to bear on the outer ends of the handles, the outer ends of the handles will approach each other, the brace or foot piece 4 will engage the object, and the hooks or jaws 7—7 will be drawn together, causing them to firmly engage the opposite sides of the object, thus enabling the operators to manipulate the same in such manner as desired.

It is obvious that the inner ends of the handles may be swingingly united by any 50 one of various well known means such, for

instance, as eye bolts or screws engaging each other, universal joint, etc., as shown in Figures 5, 6 and 7.

I claim:

1. In a device of the character described, 55 a pair of handles swingingly joined at their inner ends, and a bar loosely attached to each handle intermediate its ends and suspended at substantially right angles thereto, each of said bars carrying at its free or 60 swinging end a hook or jaw member,—said two bars being pivoted together adjacent their centers.

2. In a device of the character described, 65 a pair of handles swingingly joined at their inner ends, a depending shoe rigidly attached to the inner end of one of said handles, and a bar loosely attached to each handle intermediate its ends and suspended at substantially right angles thereto, each of 70 said bars carrying at its free or swinging end a hook or jaw member,—said two bars being pivoted together adjacent their centers.

3. In a device of the character described, 75 a pair of handles, each carrying at its inner end a hinge member, said two members being swingingly united, and a bar loosely attached to each handle intermediate its ends and suspended at substantially right angles 80 thereto, each of said bars carrying at its free or swinging end a hook or jaw member,—said two bars being pivoted together adjacent their centers.

4. In a device of the character described, 85 a pair of handles, each carrying at its inner end a hinge member, said two members being swingingly united, a depending shoe rigidly attached to the inner end of one of said handles, and a bar loosely attached to 90 each handle intermediate its ends and suspended at substantially right angles thereto, each of said bars carrying at its free or swinging end a hook or jaw member,—said two bars being pivoted together adjacent 95 their centers.

In testimony whereof, I have hereunto affixed my signature.

CHARLES V. MAMMEN.
